UNITED STATES PATENT OFFICE.

THOMAS B. JEFFERY, OF CHICAGO, ILLINOIS.

VELOCIPED.

SPECIFICATION forming part of Letters Patent No. 275,917, dated April 17, 1883.

Application filed January 22, 1883. (No model.)

To all whom it may concern:

Be it known that I, THOMAS B. JEFFERY, a citizen of the United States, residing at Chicago, in the county of Cook and State of Illinois, have invented a new and useful Velocipede, of which the following is a specification.

My invention relates to improvements in velocipedes; and the objects of my improvement are to provide a secure fastening for the center screw in the fork of the steering-wheel, means for fastening the backbone in the rear fork, means for adjusting the rear wheel in the rear fork and the front wheel in the front fork, also an improved spring to the seat. I attain these objects by the mechanism illustrated in the accompanying drawings, in which—

Figure 1 is a back view of the back fork, with section of part of the backbone; Fig. 2, a view of the steering-wheel, fork, and head; Fig. 3, a section of the front-wheel bearing, and Fig. 4 a side view of the same.

Similar letters refer to like parts throughout the several views.

The fork A, having head B, is pivoted to the reach C by a point or pivot under the neck, and by the usual center above, turning under the screw d, to which it is fitted, and by which it may be adjusted. As this screw is liable to become loose by the vibrations incidental to the use of the velocipede, I provide a set-screw, e, placed in front of the same to be out of the way of the rider's dress, the center screw being protected from injury by a metal disk placed between the point of the screw e and the side of the screw d. The backbone or reach is made of tubing and tapered in the usual way; but at the lower end of the tapered portion is formed a shoulder, F, below which a smaller tapered portion continues, and is made to fit a corresponding cavity in the upper end of the back fork, G, the shoulder on the backbone being made of such size as to be about uniform with the outside of the fork. These parts are held together by being driven into each other, and their displacement prevented by a screw or rivet. A step, H, is usually secured to the tube above the fork. This manner of fastening being unreliable, I form the step with a tube permanently attached by being cast or forged in one piece, the tube forming the upper end of the back

fork. The step has a stem or bracket extending out from the tube and continued up above the same where the step is formed, thus reaching above and partly concealing the joint. 55 This mode of constructing the step makes the accidental loosening of it impossible. The rear wheel is formed with the usual cone-shaped cavities to fit a corresponding axle; but instead of providing an axle I form on the 60 inside of the fork ends, and of the same piece of metal, cone-shaped projections I, on which the wheel can turn, and I prevent the forks from spreading by a bolt placed through the fork ends and the hub, but not necessarily fitting either. The use of the bolt permits of the necessary adjustment of the fork to the wheel, when required. The front wheel is provided with the ordinary shaft, L, and case M, containing loose steel balls forming the bearings. 70 The outer form of the case is spherical, having two sections removed, leaving two parallel sides pierced for the axle. The case is contained in a yoke or cavity shaped to conform to the case and formed at the lower end of 75 the fork. This mode of connecting the ball-cases prevents the balls being bound by a twisting strain or bend occurring in the forks by the use of the machine on rough roads or through an accident. The balls contained in 80 the case partly rest in the groove formed on the inner edge of the crank-boss, thus dispensing with an intermediate sleeve usually employed for the purpose, and allowing the opposite cranks to be placed nearer to each other 85 than they could be if the intermediate ring or sleeve were used, and partly on a similar groove on a shoulder formed on the shaft or axle, all being contained in the case. Means for adjusting the bearing are provided by the use of 90 the screw O, entering the end of the axle, which draws the crank P toward the balls, and the crank is kept from turning by the key Q, passing through the crank and at the side of the axle bearing on a flattened portion formed 95 for that purpose. The seat R, Fig. 2, is joined to the neck of the backbone by ears which embrace it and held by a pin, on which it can turn vertically within certain obvious limits below and at the rear of the seat, and supported by the perch is a wire spiral spring, S, 100 forming an elastic support for the seat.

I am aware that prior to my invention a centering-pin has been formed upon an internally-screw-threaded cap working on a externally-screw-threaded head, said cap being locked by a lateral set-screw passing through the cap and impinging against the head; but such construction is found to be objectionable, owing to the necessary limited externally-screw-threaded surface possible on the head, not affording sufficient surface to prevent the cap from soon working loose, and, besides, limiting the adjustment of the cap, which must be done as the centering-pin becomes worn. Furthermore, a greater objection exists by reason of the unavoidable shifting of the set-screw from the front to the side or rear of the machine in the way of the clothing or person of the rider as the centering-pin and neck become worn and the cap is turned to take up the wear. By my construction the adjustment of the centering-pin is substantially and practically unlimited, and the set-screw always remains at a point in front of and out of the way of the rider, and hence all of the objections above set forth are avoided.

I claim as my invention—

- 1. In a velocipede, the open rectangular head provided with vertical and lateral screw-threaded perforations, in combination with
- o the vertical centering-screw and lateral set-screw, said set-screw adapted to be impinged against and lock the centering-screw, substantially as described.

2. The taper hollow perch provided with shoulder F and reduced taper extension, in combination with the rear fork, G, having taper socket R, into which it is connected, substantially as and for the purpose described.

3. The step H, formed in one piece with the socketed fork, and joined to the taper perch by being driven onto its rear portion, substantially as described.

4. The rear fork, G, provided with cone-shaped inner projections formed in the same piece of metal, substantially as and for the purpose described.

5. The casting of rear fork having socket R and step H on its upper end, substantially as and for the purpose described.

6. The bearing-cases M, of spherical shape, embracing the balls and shaft L, and contained in spherical cavities in the fork ends, substantially as described, for the purpose set forth.

7. The crank P of a velocipede having the inner edge of its boss formed to fit a series of balls that roll thereon, in combination with the case covering the crank-boss and balls, substantially as described, for the purpose set forth.

THOS. B. JEFFERY.
